UNITED STATES PATENT OFFICE.

HENRY W. MEAD, OF QUINCY, ILLINOIS.

BRICK-MACHINE.

SPECIFICATION forming part of Letters Patent No. 471,677, dated March 29, 1892.

Application filed May 15, 1891. Serial No. 392,883. (No model.)

To all whom it may concern:

Be it known that I, HENRY W. MEAD, a citizen of the United States, residing at Quincy, in the county of Adams and State of Illinois, have invented a new and useful Brick-Machine, of which the following is a specification.

This invention relates to brick-machines; and it may be described as being an improvement on the machines of this class for which Letters Patent of the United States Nos. 386,333 and 406,754 have been issued to me on July 17, 1888, and on July 9, 1889, respectively.

15 My present invention has for its object to provide a machine which shall be exceedingly simple, compact, durable, and efficient in operation; and with these ends in view the invention consists in the improved construction, arrangement, and combination of parts, which will be hereinafter fully described, and particularly pointed out in the claims.

20 In the drawings hereto annexed, Figure 1 is a perspective view of a brick-machine constructed in accordance with my invention. Fig. 2 is a plan view of the same. Fig. 3 is a side elevation. Fig. 4 is a vertical sectional view taken centrally through the plunger carrying the lower followers and through the 25 cam operating said plunger. Fig. 5 is a vertical sectional view taken at one side of said plunger through one of the star-wheels. Fig. 6 is a detail side elevation. Fig. 7 is a detail transverse sectional view of the upper end 30 of the plunger carrying the lower followers. Fig. 8 is a detail plan view of the mold. Fig. 9 is a vertical sectional view of the same. Fig. 10 is a detail perspective view of the main shaft having the operating-cams. Fig. 40 11 is a detail perspective view of one of the star-wheels. Fig. 12 is a detail perspective view of one of the upper plungers. Fig. 13 is a detail view showing in elevation the shaft having the star-wheels and the shaft having 45 the cams engaging the latter. Fig. 14 is a sectional detail view of the lower portion of one of the upper plungers.

Like numerals of reference indicate like parts in all the figures.

50 The frame of my improved brick-machine comprises the base 1, the side pieces or up-

rights 2 2, and the top or table 3. The latter is preferably composed of the front and rear pieces 4 and 5, the latter of which is provided with side flanges 6 and with front and rear flanges 7 and 8. The side flanges may be fitted closely between the side pieces or uprights 2 2, to which they are secured by means of bolts 9. The front piece 4 may be also provided with side flanges 10 and with front and rear flanges 11 and 12. The side flanges 10 are supported upon shoulders or flanges 1^a upon the inner sides of the side pieces or uprights, and the rear and front edges of the front and rear pieces 4 and 5, respectively, are provided with shoulders 2^a to support the mold 3^a, which is provided with flanges 4^a to rest upon said shoulders. The mold, as will be seen, is thus held securely in position between the sections 4 and 5 of the table and may be 60 additionally secured by means of wedges 5^a, driven between the upper side edges of the mold-box and the undersides of wedge-shaped projections 6^a upon the inner sides of the uprights 2 2. The front section 4 of the table is 65 preferably provided with laterally-extending ears or lugs 7^a, having perforations to receive bolts, by means of which it is secured to the uprights or side pieces of the frame.

The mold 3^a, as shown in detail in Figs. 8 80 and 9 of the drawings, is composed of the side pieces 8^a, having vertical grooves 9^a in their inner faces to receive the vertical end flanges 10^a of the end pieces 11^a. The mold may be provided with one or more openings to adapt 85 the machine to the manufacture of one or more bricks at each operation. When, as in the drawings hereto annexed, the mold-box is provided with two such openings 12^a, a central spacing-block 1^b is interposed between 90 the side pieces 8^a. The several parts of the mold-box are connected by means of transverse bolts 2^b, and the several parts of the said mold-box are also provided with openings or channels 3^b for the passage of steam, 95 which may be supplied through a pipe 4^b, connected with one side of the frame of the machine. This is for the obvious purpose of heating the mold. The perforations 5^b, through which the connecting-bolts 2^b extend, 100 are made slightly oblong or elongated. This is for the purpose of enabling the end blocks

11^a to be slightly raised, so as to compensate for wear.

The side pieces or uprights 2 2 of the frame are connected a short distance above the base 5 by a cross-brace 14. Suitably attached to said cross-brace 14 and to the rear side of the front flange 7 of the section 5 of the table are the guides 15 and 16 for the vertically-movable stem or plunger-head 17, the front side of 10 which is provided with a hood 18, in which is journaled a roller 19^a. The upper side of the hood 18 is provided with a block 19, having recesses 20 and vertical perforations 21 to receive the screw-threaded stems 22, extending 15 downwardly from the lower plungers 23, which may be secured in position upon the upper side of the block 19 by means of nuts 24, mounted upon the said stems within the recesses 20. The plungers 23 are thus mounted 20 upon the hood in such a manner as to fit accurately in the openings of the mold and so as to enable them to be readily removed, when desired, for the substitution of new ones. 25 designates the main shaft, which is provided 25 with suitable bearings in the side pieces 2 of the frame. Said main shaft is provided with a cam 26, adapted to engage the roller 19^a in the hood of the stem or plunger 17, which is in this manner operated.

30 The cam 26, as will be clearly seen in Fig. 4 of the drawings, has the preliminary swell 27 and the main swell 28, so that in the operation of the machine the plunger-head shall first be moved slowly in an upward direction 35 for a short distance for the purpose of giving the final pressure to the bricks, after which, by means of the swell 28, the plunger-head is forced more rapidly in an upward direction for the purpose of expelling the bricks, all as 40 will be hereinafter more fully described. The side pieces or uprights 2 2 of the frame are provided near their upper ends with vertical slots 29, forming bearings for the cross-head 30, having the depending arms 31, one at each 45 end, said arms being arranged outside of the side pieces of the frame. Guide-plates 6^b, arranged adjacent to the sides of said slots, are secured by means of bolts 7^b, extending through oblong slots or perforations in the 50 said plates, which are thereby rendered laterally adjustable to compensate for wear.

The arms 31 are provided with openings 32 to admit the main shaft and to enable the said arms, with the cross-head, to move freely in 55 an upward and downward direction. To the other sides of the arms 31, respectively above and below the slots or openings 32, are journaled rollers 33 and 33^a, which are adapted to be engaged by cams 34, formed or mounted 60 upon the main shaft. These cams, when engaging the roller 33, serve for the purpose of raising or lifting the cross-head after the bricks have been formed and are ready to be expelled from the press. When engaging the 65 lower rollers 33^a, the said cams serve to assist the downward movement of the arms and cross-head, although, as will be presently seen,

the said cams are not relied upon to exert the entire downward pressure upon the said arms and cross-head.

The lower ends of the arms 31 have bearings for a transverse shaft 35, upon which are mounted a pair of the star-shaped wheels 36. Said wheels, as their name indicates, are provided with radial arms 37, separated by recesses 38, the recesses being for the purpose of accommodating the main shaft 25 when the arms carrying the cross-head are in a raised position. The main shaft 25 is provided with cams 39, adapted to engage with 80 arms 37 of the star-wheels for the purpose of forcing the latter, the shaft 35, the arms 31, and the cross-head 30 in a downward direction to assist in finally compressing the bricks, the engagement of said cams 39 with the star-wheels being timed to take place at the same time when the swell 27 of the cam 26 engages the roller 19^a in the hood of the plunger-head 17.

It is obvious that the side pieces or uprights of the frame are to be provided with vertical slots or openings, as will be seen at 39^a, for the passage of the shaft 25, carrying the star-wheels, and to enable the ends of said shaft to be journaled in the arms 31.

95 The cross-head 30 is provided with vertical perforations 40 to receive the screw-threaded stems 41 of the upper plungers 41^a, which are secured by means of nuts 42. Said plungers of course are arranged so as to register with the openings of the mold, and it will be understood that they may be readily removed or readjusted whenever required.

The preferred construction of the upper plunger of my improved brick-machine has 105 been shown in detail in Figs. 12 and 14 of the drawings. Said plungers are provided at their lower edges with flanges 40^b, accurately fitting the openings of the mold and provided with tapering holes or openings 41^b, the lower ends of which are considerably contracted in order to prevent clay from escaping through the said openings, which latter are merely for the purpose of permitting the escape of air, thereby preventing the formation of air-bubbles in the bricks that are being pressed.

110 The arms 37 of one of the star-wheels are provided at their front ends with outwardly-extending studs or projections 43. Similar studs 44 project outwardly from the rear ends 120 37 of the arms of the other star-wheel, as will be best seen in Fig. 13 of the drawings. The cams 39 are provided with recesses 45 and 46, adapted to engage the studs 43 and 44, respectively. By this mechanism the shaft carrying the star-wheels is partially rotated when the cams 39 engage the outer ends of the arms 37, the extent of the rotation being sufficient 125 to cause the main shaft to engage the next recess 38 when the frame composed of the shaft 35, carrying the star-wheels, the arms 31, and the cross-head 30 is again forced in an upward direction by the action of the cams 34, engaging the rollers 33 upon the arms 31. Cogs

may be substituted for the studs 43 and 44; but I prefer the latter ordinarily, because but little strain comes on them, and the face of the star-wheel sections is by their use left 5 smooth and circumferentially flat, whereby a better engaging surface is secured for contact with the cams. To retain the shaft 35 in the position to which it is carried by cams 39 engaging the arms of the star-wheels, dogs or 10 pawls 47 are provided, which may be pivoted to the inner side pieces or uprights 2 of the frame, suitable springs 49 being preferably provided to hold the said pawls in contact with the adjacent star-wheels. The cams 39 15 will engage the upper or free ends of the pawls 47 to throw the latter out of engagement with the star-wheels while the latter are being partially rotated.

To regulate the extent of the downward- 20 movement of the stem or plunger-head carrying the lower plungers, I provide an arm 50, hinged to the rear part of the base and extending forwardly under the said stem, for which it is adapted to form a support.

25 51 designates a vertical rod, the upper end of which is journaled in a cross-bar 48 of the frame and the lower end of which is screw-threaded, as shown at 52, and engages a screw-threaded socket or perforation 52^a in the base.

30 Upon the rod 51 above the screw-threaded portion is formed a flange 53, supporting a stiff spring 54, upon which the front end of the arm 50 rests, said arm being provided with a perforation 55 for the passage of said rod.

35 It will be seen that by rotating the screw-threaded rod 51, which latter is provided for the purpose with a hand-wheel 56, the front end of the arm 50 may be raised or lowered, thus regulating the extent to which the plunger-head and the lower plungers shall be per-

40 mitted to descend. In this manner the capacity of the mold may be very accurately gauged or regulated, causing it to receive a greater or smaller quantity of material to be 45 molded, as may be desired, according to the condition of the material and the required density of the product produced by the machine.

The main shaft 24 is provided at one end 50 with a gear-wheel 57, upon the outer side of which is mounted a cam-grooved disk 58. Suitably mounted in the rear part of the frame is a transverse rock-shaft 59, having a forwardly-extending arm or lever 60, which 55 is provided at its front end with a roller 61, traveling in the cam-groove 62 of the disk 58. The rock-shaft 59 is also provided with an upwardly-extending arm or lever 63, the upper end of which is connected by a link 64 60 with a feed-box 65. The latter slides upon the top of the table beneath a hopper 66, in which the prepared clay or other material is placed. Said feed-box serves not only to supply the material from the hopper 66 to the 65 mold, but also to push the previously-formed bricks from off the lower plungers onto the front part of the table, where they may be

readily removed, the feed-box being actuated by the link 64, levers 60 and 63, rock-shaft 59, and cam-groove 62, engaging the roller 61, 70 said cam-groove being so formed as to cause the operation of the feed-box to be properly timed—that is, while the lower plungers are in an elevated position flush with the table.

The gear-wheel 57 upon the main shaft 75 meshes with a spur-wheel 67 upon one end of a shaft 68, which is journaled transversely in the rear part of the frame. The opposite end of the shaft 68 carries a gear-wheel 69, meshing with a pinion 70 upon a shaft 71. 80 The latter also has the drums or band-wheels 75 and 75^a, one loose and the other fixed, and adapted to receive motion from power of any desired description.

It is obvious that the train of gearing just 85 described is used merely for the purpose of reducing speed and that different gearing may be employed without departing from my invention.

The top of the table of the machine is provided with guide-plates 76, preferably having upwardly-extending flanges 77, between which the feed-box is guided. Said guide-plates are secured adjustably by means of screws 78, so that wear may be compensated 90 for and the feed-box be caused to operate evenly and accurately. The front ends of the guide-flanges 77 are for convenience curved outwardly, as shown at 79.

The operation of my invention is as follows: While the upper and lower plungers are in a raised position the feed-box is moved forwardly, carrying a portion of the clay from the hopper, the lower end of said hopper being meanwhile closed by the horizontal plate 100 82, which forms a part of the feed-box. While the feed-box is in a forward position the cam 26 abruptly passes from under the roller 19^a in the hood 18 of the stem or plunger-head 17, thus causing the lower plungers to 105 descend somewhat rapidly by their own weight added to that of the stem and hood to which they are attached. The clay or other material then drops by gravity and is also drawn into the openings of the mold by the suction 110 induced by the withdrawal of the plungers. The feed-box is then retracted, leveling up the mold, and the upper plungers now begin to descend, at first rapidly as the cams 34 115 pass from under the rollers 33 and afterward more slowly and forcibly by the action of the cams 39, engaging the arms 37 of the star-wheels. At this time the swell 27 of the cam 26 begins to engage the roller 19^a, forcing the lower plungers in an upward direction, and thus compressing the bricks or other product.

As the cams 39 pass out of engagement with the arms 37 of the star-wheels the cams 34 begin to engage the rollers 33, thus forcing the arms 31, carrying the cross-head, and the upper plungers in an upward direction, the main shaft being accommodated, while this upward movement takes place, in the recesses 38 of the star-wheels. At the same time the

lower plungers are forced with the same speed also in an upward direction by the action of the swell 28 of the cam 26. Thus during the 5 passage of the bricks through the mold for delivery therefrom they are subject to the pressure of the plungers on both sides. Consequently cracking or crumbling is avoided. When, however, they reach the level of the 10 table then the increased throw of the cams 25 lift the upper plungers more rapidly than the lower ones and the pressure is thus relieved during the time that the product is unsustained by the molds. The feed-box now repeats its movement in a forward direction, 15 pushing the bricks or other produce onto the front part of the table and supplying the mold again with material, after which the operation is repeated.

It is obvious that certain features of my 20 invention are applicable to other machines than brick-machines. I therefore do not restrict my invention to them, and it is also obvious that many alterations or equivalent mechanical constructions may be substituted for some 25 of the parts shown and described by me. I therefore do not limit myself to such details.

Having thus described my invention, I claim and desire to secure by Letters Patent—

30 1. In a molding or like machine, the combination, with a reciprocating stem or plunger-head carrying a plunger, of a frame comprising a reciprocating cross-head carrying another plunger, depending arms, and a transverse shaft journaled in said arms, star-wheels 35 mounted on said shaft, and a main shaft carrying cams for operating the several plungers, said main shaft being extended through openings in the said arms and adapted to be 40 accommodated, when said frame is moved, in the recesses of the star-wheels, substantially as set forth.

2. In a molding or like machine, the combination of a frame, a main shaft journaled in 45 the sides of said frame and having operating-cams, and an upper-plunger frame having a transverse shaft provided with star-wheels the radial projections of which form cams adapted to be engaged by cams upon the main shaft 50 and the recesses of which are adapted to accommodate said main shaft during the movement of the plunger-frame, substantially as set forth.

3. In a molding or like machine, the combination, with a reciprocating plunger-frame 55 having a transverse shaft, of star-wheels mounted upon said shaft and provided with

studs or like devices extending outwardly from the projecting portions thereof, and the main shaft extending through openings in the 60 arms of the plunger-frame and having cams provided with recesses to engage the studs of the star-wheels, substantially as and for the purposes set forth.

4. In a molding or like machine, the combination of the upper-plunger frame, the main shaft having cams to force said frame in an upward direction, a shaft journaled transversely between the side pieces of the upper-plunger frame, star-wheels mounted upon 70 said shaft, cams upon the main shaft, adapted to engage said star-wheels to force the upper-plunger frame in a downward direction, and a pawl pivoted to the main frame and adapted to engage one of the star-wheels, substantially as set forth.

5. In a molding or like machine, the combination of the side pieces or uprights having wedge-shaped projections upon their inner sides, the front and rear sections of the bed 80 or table having downwardly-extending flanges and secured detachably between said uprights or side pieces, said table-sections being provided with shoulders at their upper inner edges, a mold having flanges resting upon 85 said shoulders, and the wedges driven between the ends of said mold and the wedge-shaped projections upon the inner sides of the uprights, substantially as set forth.

6. In a molding or like machine, the combination of the side pieces or uprights, the rear table-sections having downwardly-extending flanges and secured by means of bolts to the 90 said uprights, the horizontal flanges, and wedge-shaped projections formed upon the inner sides of the uprights, a front table-section having downwardly-extending flanges resting upon the horizontal flanges of the uprights and provided with laterally-extending ears or lugs bolted to said uprights, the mold 100 having flanges resting upon shoulders at the upper inner edges of the front and rear table-sections, and the securing-wedges driven between the ends of said molds and the wedge-shaped projections upon the inner sides of 105 the uprights, substantially as set forth.

In testimony that I claim the foregoing as my own I have hereto affixed my signature in presence of two witnesses.

HENRY W. MEAD.
